(57) CLAIM

The ornamental design for an audio system enclosure, as shown and described.

DESCRIPTION

FIG. 1 is a perspective view of an audio system enclosure showing the top, front, and right sides of our new design; FIG. 2 is a right side elevational view of the audio system enclosure of FIG. 1, the left side elevational view being a mirror image thereof;

FIG. 3 is a front elevational view of the audio system enclosure of FIG. 1;

FIG. 4 is a rear elevational view of the audio system enclosure of FIG. 1;

FIG. 5 is a top plan view of the audio system enclosure of FIG. 1; and,

FIG. 6 is a bottom plan view of the audio system enclosure of FIG. 1.

The broken line showing on FIG. 4 is for illustrative purposes only and forms no part of the claimed design.
